SELF-SEALING DOOR

Franz Doll, Essen, Germany, assignor, by mesne assignments, to Koppers Company, Inc., Pittsburgh, Pa., a corporation of Delaware

Application December 6, 1952, Serial No. 324,571

8 Claims. (Cl. 202—248)

The invention relates to self-sealing doors for horizontal coke ovens or the like, such doors being of the kind having latch bars adapted to engage latch hooks projecting from the door frame, and having a sealing frame mounted on the door in a circumferential recess.

Coke oven doors are known in which a web-like or flat sealing frame is mounted, with an asbestos packing, in a circumferential recess in the door body in order to prevent escape of gas. However, sealing frames mounted in this manner can only with difficulty be kept leak-proof because of the constant movement to which such frames are subjected by the positioning of the door, and in addition, the sealing frame is made more or less rigid and only has a slight degree of resilience to adapt itself to the irregularities of the door frame which occur in operation.

The present invention provides a door having a sealing frame which provides a high degree of resilience and also satisfactory sealing conditions at the point of connection of the sealing frame with the door body and while pressed against the door frame of a coke oven door in closed position of the door. Moreover, a door constructed in accordance with the present invention also has the advantage, that it does not require mountings on the door body for the pressure screws for the sealing frame, so that there is ample space for introducing a wide levelling bar into an oven closed by such door.

A door constructed in accordance with the present invention is characterised in that the sealing member in the form of a frame is Z-shaped in cross-section and bears with the free edge of one of its limbs against the sealing surface of the door frame of a coke oven and is mounted imperforately with its other limb gas-tightly sealed in the said circumferential recess in the door body.

Such a construction and imperforate mounting of the sealing frame on the door provides greater resilience for the limb which bears against the sealing surface on the coke oven, whereby the imperforately clamped limb sealed in the recess in the door body can be pressed so firmly against the latter by stud screws laterally through an outer side wall of the recess against an inner wall thereof that in practice scarcely any displacements of the said clamped limb take place and thus the sealing at the clamping point is only slightly stressed.

According to a further feature of the invention, the resilience of the sealing frame may be increased by furnishing the web between the two limbs of the Z-shaped sealing frame with longitudinal recesses.

Furthermore, according to the invention, that limb of the Z-shaped sealing frame which is sealed in the said recess in the door body may be clamped, by pressure screws arranged laterally in the outer wall of the recess, against sealing means arranged in said recess to form a caulked joint between said limb and the door body. This caulked joint preferably bears against a comparatively narrow region of the bearing surface of the limb of the sealing frame, so that the major bearing surface part of said limb only requires a comparatively thin packing.

At the four rectangular corners of the door body, however, the caulked joint is preferably enlarged to extend over the entire bearing surface of the limb of the sealing frame, so that the latter can be reliably fitted even when the cast door body is not accurately machined at the corners.

According to a further feature of the invention, the sealing frame may be pressed against the door frame by means of pressure screws which are adjustably mounted in lugs on the door body and which bear against the limbs of the sealing frame for abutting the door frame therefor on a coke oven.

According to yet another feature of the invention, a compression spring may be arranged between each of the latter said pressure screws, and pistons which act on the sealing frame and which are displaceably mounted in bores in the said lugs.

As a result of such resilient mounting of the pressure means of the sealing frame, the resilience of the sealing frame is such that the latter can easily accommodate all irregularities of the door frame and the door itself which may occur in operation.

In order to be able to determine at what points compression of the springs may have to be adjusted as a result of deformation of the door frame or door body, the said pistons may each be provided with a stem which so passes through a bore in its associated adjustable pressure screw that the end of the stem is visibly flush with the visible end of the pressure screw when the spring associated therewith is under its proper compression; thus it is possible at any time to carry out a simple adjustment of the spring pressure to compensate for door frame or door body deformation by adjusting pressure screws until the ends thereof are visibly flush with the ends of the said piston stems.

One embodiment of the invention is shown by way of example in the accompanying drawing, wherein:

Figure 1 is a horizontal section of a door constructed in accordance with the invention, the door being in the closed position in a door frame of an oven chamber; and

Figure 2 is an enlarged horizontal section of the means by which the sealing frame is imperforately secured in the door body and pressed against the door frame.

As shown in the drawings, a refractory plug 1, carried by the door body 9 which is of cast iron, projects into the oven chamber 2 when the door is in its closed position.

The oven comprises refractory walls 3, in which are disposed heating flues 4, between the individual oven chambers, the front ends of the walls 3 being covered by a refractory insulating layer 5. The refractory insulating layer 5 of the oven battery is lined with an iron reinforcement 6 against which bears the door frame 7 surrounding each opening of the oven chamber, said frame 7 being connected by suitable means such as screws or the like with the iron reinforcement 6.

The inner refractory plug 1 is embraced by a frame 8 having a flange by which it is connected with the cast-iron door body 9. The rugged outer metallic cast-iron door body 9 is formed with a peripheral web 10 which has a fork-like section at its junction with the body 9 so that an inwardly open circumferential recess 11, of U-shape in cross-section, is formed as clearly shown in the drawings. A rectangular circumferential sealing frame 12 having a Z-shape cross-section is mounted by means of one of its limbs 13 in the U-shaped recess 11; the other limb 14 of the sealing frame 12 bears against a sealing surface 15 on the door frame 7 when the door is in the closed position. The gas-tight mounting of the limb 13 in the recess 11 is effected by pressure screws 16 which pass at intervals through the outer wall of the recess 11 and as studs press the limb 13 imperforately against a packing, for example, of asbestos, which is

mounted to form a caulked joint 17 on the inner wall forming the U-shaped recess. This caulked joint 17 is disposed on the oven side of the axes of the pressure screws 16, so that only a comparatively thin asbestos plate 18 or the like is necessary to seal the remainder of the limb 13 in the recess 11.

Such an asbestos plate 18 is sufficient on the vertical longitudinal and horizontal transverse surfaces of the recess 11, since these surfaces will be substantially flat after the casting of the cast iron body 9 and its peripheral web 10. However, at the four corners of the door, owing to the danger of irregularities during casting, the caulked joint 17 is enlarged (as indicated by the dotted lines 17' in Figure 2) in such manner that the entire corner portions of the surface of the limb 13 bears against the caulked joint. The web 19 connecting the two limbs 13 and 14 of the sealing frame 12 is formed with longitudinal recesses 20 which give a satisfactory degree of resiliency to the sealing frame.

In the closed position of the door, pistons 21 act on the limb 14 of the sealing frame, said pistons being mounted for axial displacement in bores 22 of lugs 23. The lugs 23 are preferably integrally cast with the outer wall of the recess 11. Each bore 22 is formed with an internal thread into which is screwed a pressure screw 24, the screw 24 having a bore 25 through which extends a stem 26 of the piston 21. A set of plate springs 27 is arranged between the piston 21 and the inner end of the screw 24, these springs being of such strength that the necessary bearing pressure of the sealing frame 12 upon the surface 15 of the door frame 7 is attained when the screw 24 is screwed so far into the thread of the bore 22 that, when the door is closed, the end of the stem 26 of the piston 21 is flush with the outer end of the screw 24.

When local irregularities of the sealing surface 15 of the door frame 7 occur, the stem 26 shows beyond the head of the screw 24. By unscrewing the screw 24 to such an extent that the end of the stem 26 is again flush with the outer end of the head of screw 24, the normal closing pressure of the springs 27 is restored.

The door is locked in its closed position by means of latch bars 28, rotatably mounted on latch bolts 29, which latch bars are adapted to engage with latch hooks 30 connected to the door frame 7. The latch bolts 29 are mounted in bearings forming a part of housing 31 connected with the door body 9. Preferably the closing pressure of the door is produced by springs which are shown mounted in the housing 31, such springs urging the latch bars 28 away from the door body 9. Upon fitting the door, these closing springs must be compressed somewhat by means of the latch bolts 29, this compression being relieved after swinging the bars 28 into engagement with the hooks 30. The compression of the closing springs is obtained either by rotating the latch bolts 29 or by axial pressure for instance, pneumatic pressure, applied to the latch bolts 29 and the collar for the latch bars by the door-handling machine.

The invention as hereinabove set forth is embodied in particular forms and manners, but may be variously embodied within the scope of the claims hereinafter made.

What I claim is:

1. A self-sealing coke oven door comprising a door body; a rectangular circumferential sealing frame recess on said door body in surrounding relation therewith comprising in cross-section oppositely disposed inner and outer side walls and an open entrance passage between the side walls facing toward a coke oven doorway in closed position of the door; a rectangular sealing frame of Z-shape in cross-section, having longitudinal recesses in the web between the two limbs of the Z-shape of the frame, arranged in surrounding relation with the door body with one limb extending from the web inwardly of the door and terminating in a free sealing edge in position for sealing engagement against a sealing surface therefor on a door frame for the door in its closed position on a coking chamber; and with the other limb of the Z-shape, extending from the web of the frame outwardly of the door and freely slidably into and out of the circumferential recess alongside the inner wall through its open entrance passage from the inner side of the door; pressure stud screws accessible for manipulation from the exterior of the frame recess and extending laterally through the outer side wall of the frame recess and into the recess space between the inner and outer walls thereof in pressure abutting imperforate relation with the limb of the frame alongside the inner wall in

tion on a coking chamber, and with the other limb of the Z-shape extending from the web of the frame outwardly of the door and freely slidably into and out of the circumferential recess alongside the inner wall through its open entrance passage from the inner side of the door; pressure stud screws accessible for manipulation from the exterior of the frame recess and extending laterally through the outer side wall of the frame recess and into the recess space between the inner and outer walls thereof in pressure abutting imperforate relation with the limb of the frame alongside the inner wall in the frame recess, for imperforately clamping said limb gas tight against said inner wall; said inner side wall being spaced a distance closer to the axis of the door body in the region between the stud screws and the web of the Z-shaped frame throughout the longitudinal and horizontal parts of the recess, than in the region between the stud screws and the outer free edge of the limb in the recess, for caulking the space between said inner wall of the recess and the limb of the Z-shape frame therein, from the inner side of the door, with packing that is thicker throughout the longitudinal and horizontal parts of the limb in the recess, in the region between the stud screws and the web of the Z-shape frame, than in the region alongside the inner wall of the recess between the stud screws and the outer free edge of the limb in the recess; and adjustable pressure means mounted alongside, and accessible from the exterior of, the outer side wall of the circumferential rectangular frame recess, for exerting sealing pressure on the inwardly extending limb to its terminal free sealing edge against a sealing surface on a door frame in closed position of the door, said adjustable pressure means each comprising a piston acting on the limb, an adjustable screw, a pressure transmitting spring interposed between the piston and the adjustable screw, a bore in the adjustable screw, and a stem on the piston extending through the bore and terminating in an outwardly visible flush relation with an outwardly visible surface of the adjustable screw, when the door is closed with the spring at normal sealing pressure.

2. A coke oven door as claimed in claim 1, and in which the portions of the inner side wall of said recess at the corners of the rectangular circumferential sealing frame recess are at a greater distance closer to the axis of the door body alongside the portions of the limb from the web to the free edge of the limb than the distance of the portions of the inner wall of the recess alongside the portions of the limb between the stud screws and the outer free edge of the limb in the region between the corners of the recess frame.

3. A self-sealing coke oven door comprising: a door body; a rectangular circumferential sealing frame recess on said door body in surrounding relation therewith comprising in cross-section oppositely disposed inner and outer side walls and an open entrance passage between the side walls facing toward a coke oven doorway in closed position of the door; a rectangular sealing frame of Z-shape in cross-section, having longitudinal recesses in the web between the two limbs of the Z-shape of the frame, arranged in surrounding relation with the door body with one limb extending from the web inwardly of the door and terminating in a free sealing edge in position for sealing engagement against a sealing surface therefor on a door frame for the door in its closed position on a coking chamber; and with the other limb of the Z-shape, extending from the web of the frame outwardly of the door and freely slidably into and out of the circumferential recess alongside the inner wall through its open entrance passage from the inner side of the door; pressure stud screws accessible for manipulation from the exterior of the frame recess and extending laterally through the outer side wall of the frame recess and into the recess space between the inner and outer walls thereof in pressure abutting imperforate relation with the limb of the frame alongside the inner wall in

the frame recess, for imperforately clamping said limb gas tight against said inner wall; said inner side wall being spaced a distance closer to the axis of the door body in the region between the stud screws and the web of the Z-shaped frame throughout the longitudinal and horizontal parts of the recess, than in the region between the stud screws and the outer free edge of the limb in the recess, for caulking the space between said inner wall of the recess and the limb of the Z-shape frame therein, from the inner side of the door, with packing that is thicker throughout the longitudinal and horizontal parts of the limb in the recess, in the region between the stud screws and the web of the Z-shape frame, than in the region alongside the inner wall of the recess between the stud screws and the outer free edge of the limb in the recess; and adjustable pressure means mounted alongside, and accessible from the exterior of, the outer side wall of the circumferential rectangular frame recess, for exerting sealing pressure on the inwardly extending limb to its terminal free sealing edge against a sealing surface on a door frame in closed position of the door.

4. A self-sealing coke oven door comprising: a door body; a circumferential sealing frame recess on said door body in surrounding relation therewith comprising in cross-section oppositely disposed inner and outer side walls and an open entrance passage between the side walls facing toward a coke oven doorway in closed position of the door; a sealing frame of Z-shape in cross-section, having longitudinal recesses in the web between the two limbs of the Z-shape of the frame, arranged in surrounding relation with the door body with one limb extending from the web inwardly of the door and terminating in a free sealing edge in position for sealing engagement against a sealing surface therefor on a door frame for the door in its closed position on a coking chamber, and with the other limb of the Z-shape extending from the web of the frame outwardly of the door and freely slidable into and out of the circumferential recess alongside the inner wall through its open entrance passage from the inner side of the door; pressure stud screws accessible for manipulation from the exterior of the frame recess and extending laterally through the outer side wall of the frame recess and into the recess space between the inner and outer walls thereof in pressure abutting imperforate relation with the limb of the frame alongside the inner wall in the frame recess, for imperforately clamping said limb gas tight against said inner wall; said inner side wall being spaced a distance closer to the axis of the door body in the region between the stud screws and the web of the Z-shaped frame throughout the longitudinal and horizontal parts of the recess, than in the region between the stud screws and the outer free edge of the limb in the recess, for caulking the space between said inner wall of the recess and the limb of the Z-shape frame therein, from the inner side of the door, with packing that is thicker throughout the longitudinal and horizontal parts of the limb in the recess, in the region between the stud screws and the web of the Z-shape frame, than in the region alongside the inner wall of the recess between the stud screws and the outer free edge of the limb in the recess; and adjustable pressure means mounted alongside, and accessible from the exterior of, the outer side wall of the circumferential frame recess, for exerting sealing pressure on the inwardly extending limb to its terminal free sealing edge against a sealing surface on a door frame in closed position of the door.

5. A self-sealing coke oven door comprising: a door body; a circumferential sealing frame recess on said door body in surrounding relation therewith comprising in cross-section oppositely disposed inner and outer side walls and an open entrance passage between the side walls facing toward a coke oven doorway in closed posi-

tion of the door; a sealing frame of Z-shape in cross-section, arranged in surrounding relation with the door body with one limb extending from the web inwardly of the door and terminating in a free sealing edge in position for sealing engagement against a sealing surface therefor on a door frame for the door in its closed position on a coking chamber, and with the other limb of the Z-shape extending from the web of the frame outwardly of the door and freely slidable into and out of the circumferential recess alongside the inner wall through its open entrance passage from the inner side of the door; pressure stud screws accessible for manipulation from the exterior of the frame recess and extending laterally through the outer side wall of the frame recess and into the recess space between the inner and outer walls thereof in pressure abutting imperforate relation with the limb of the frame alongside the inner wall in the frame recess, for imperforately clamping said limb gas tight against said inner wall; said inner side wall being spaced a distance closer to the axis of the door body in the region between the stud screws and the web of the Z-shaped frame throughout the longitudinal and horizontal parts of the recess, than in the region between the stud screws and the outer free edge of the limb in the recess, for caulking the space between said inner wall of the recess and the limb of the Z-shape frame therein, from the inner side of the door, with packing that is thicker throughout the longitudinal and horizontal parts of the limb in the recess, in the region between the stud screws and the web of the Z-shape frame, than in the region alongside the inner wall of the recess between the stud screws and the outer free edge of the limb in the recess; and adjustable pressure means mounted alongside, and accessible from the exterior of, the outer side wall of the circumferential frame recess, for exerting sealing pressure on the inwardly extending limb to its terminal free sealing edge against a sealing surface on a door frame in closed position of the door, said adjustable pressure means each comprising a piston acting on the limb, an adjustable screw, a pressure transmitting spring interposed between the piston and the adjustable screw, a bore in the adjustable screw, and a stem on the piston extending through the bore and terminating in an outwardly visible flush relation with an outwardly visible surface of the adjustable screw, then the door is closed with the spring at normal sealing pressure.

6. A self-sealing coke oven door comprising: a door body; a circumferential sealing frame recess on said door body in surrounding relation therewith comprising in cross-section oppositely disposed inner and outer side walls and an open entrance passage between the side walls facing toward a coke oven doorway in closed position of the door; a sealing frame of Z-shape in cross-section, arranged in surrounding relation with the door body with one limb extending from the web inwardly of the door and terminating in a free sealing edge in position for sealing engagement against a sealing surface therefor on a door frame for the door in its closed position on a coking chamber, and with the other limb of the Z-shape extending from the web of the frame outwardly of the door and freely slidable into and out of the circumferential recess alongside its inner wall through its open entrance passage from the inner side of the door; pressure stud screws accessible for manipulation from the exterior of the frame recess and extending laterally through the outer side wall of the frame recess and into the recess space between the inner and outer walls thereof in pressure abutting imperforate relation with the limb of the frame alongside the inner wall in the frame recess, for imperforately clamping said limb gas tight against said inner wall; said inner side wall being spaced a distance closer to the axis of the door body in the region between the stud screws and the web of the Z-shaped frame throughout the longitudinal and hori-

zontal parts of the recess, than in the region between the stud screws and the outer free edge of the limb in the recess, for caulking the space between said inner wall of the recess and the limb of the Z-shape frame therein, from the inner side of the door, with packing that is thicker throughout the longitudinal and horizontal parts of the limb in the recess, in the region between the stud screws and the web of the Z-shape frame, than in the region alongside the inner wall of the recess between the stud screws and the outer free edge of the limb in the recess; and adjustable pressure means mounted alongside, and accessible from the exterior of, the outer side wall of the circumferential frame recess, for exerting sealing pressure on the inwardly extending limb to its terminal free sealing edge against a sealing surface on a door frame in closed position of the door.

7. A self-sealing coke oven door comprising, in combination: an inner plug member; a flexible sealing member extending around the periphery of the door; a rugged outer metallic member arranged outwardly from said sealing member; a plurality of resilient adjusting means disposed around the periphery of said outer metallic member and arranged for exerting resilient pressure on said sealing member, each said resilient adjusting means comprising a piston acting on the sealing member, an adjustable screw, a pressure transmitting spring interposed between the piston and the adjustable screw, a bore in the adjustable screw, and a stem on the piston extending through the bore and terminating in an outwardly visible flush relation with an outer visible surface of the adjustable screw, when the spring is at normal sealing pressure in the closed position of the door.

8. A self-sealing coke oven door comprising, in combination: an inner plug member; a flexible sealing member arranged around the periphery of the door; a rugged

outer metallic member arranged outwardly from said sealing member; a peripheral recess for seating said sealing member in surrounding relation with said rugged outer member, said recess comprising in cross-section oppositely disposed inner and outer side walls and an open entrance passage between the side walls and facing toward a coke oven doorway in closed position of the door; said sealing member being freely slideable into and out of the peripheral recess alongside its inner side wall through its open entrance passage from the inner side of the door; pressure stud screws extending laterally through the outer side wall of the recess for the sealing member into the recess space between the inner and outer walls thereof in pressure abutting imperforate relation with the sealing member alongside the inner wall of the recess, for imperforately clamping said sealing member gas tight against said inner wall; and a plurality of adjusting means disposed around the periphery of said rugged outer metallic member and arranged for exerting sealing pressure on said sealing member against a sealing surface therefor on a coke oven chamber in the closed position of the door.
